(57) **CLAIM**

The ornamental design for an LED light fixture with concentric heatsinks, as shown and described.

DESCRIPTION

FIG. 1 is a top perspective view of an LED light fixture with concentric heatsinks, showing the new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings are included for the purpose of illustrating unclaimed portions of the LED light fixture with concentric heatsinks and form no part of the claimed design.

1 Claim, 8 Drawing Sheets
